Int. Cl. D26—06

U.S. Cl. D48—32 A

FIG. 1 is a side elevational view of a lens embodying my novel design.

FIG. 2 is a plan view of the same.

FIG. 3 is a sectional view taken along the line 3—3 in FIG. 2.

FIG. 4 is a sectional view taken along the line 4—4 in FIG. 2.

FIG. 5 is an end view of the same.

FIG. 6 is a bottom plan view of a portion of the hexagonal faceting partially shown in FIG. 2.

The hexagonal faceting is partially shown in FIG. 2 for convenience of illustration, it being understood that the faceting is uniformly continuous over the area indicated.

I claim:

The ornamental design for a lens, as shown and described.
